A. D. Farmer & R. Rathbone. *Mould for Backing Electrotype Shells*
 N° 13521. Patented Sept. 4. 1855.

UNITED STATES PATENT OFFICE.

AARON D. FARMER AND RANSOM RATHBONE, OF BROOKLYN, NEW YORK.

IMPROVED MOLD FOR BACKING ELECTROTYPE-SHELLS.

Specification forming part of Letters Patent No. 13,521, dated September 4, 1855.

To all whom it may concern:

Be it known that we, AARON D. FARMER, of Brooklyn, Kings county, State of New York, and RANSOM RATHBONE, of the city and county of New York, and State aforesaid, have invented a new and Improved Apparatus or Mold-Block for Backing Up Electrotype-Shells; and we do hereby declare the following to be a full description of the same.

The nature of our invention consists, substantially, in the construction and application of a mold so that the body or frame of the same holds the electrotype-shell flat and securely upon the bed-plate of the mold-block while the fused type-metal is being poured into the mold to back it up, and thereby preventing the shell from warping up, and the use of numerous wires and springs heretofore used by electrotypers for that purpose; but to describe our invention more particularly we will refer to the accompanying drawings, forming a part of this specification, the same letters of reference wherever they occur referring to like parts.

Figure 1 is a perspective view of the mold-block, with the clamps attached thereto for holding the parts together. Fig. 2 is a transverse cut section of the mold-block through line $\alpha\alpha$, Fig. 1. Fig. 3 is a perspective view of the frame or body of the mold. Fig. 4 is a representation of an electrotype-shell for illustrating the application of the apparatus.

Letter A represents the bed or bottom plate of the mold. This plate is a flat plate of metal of any suitable dimensions for the size of electrotype-shells to be operated upon. At letter K is a handle attached to it for convenience of handling, as the plate is always heated for the purpose of fusing the solder on the back of the electrotype-shell.

Letter B is a hollow frame composing the sides of the mold. The lower edges of this frame are beveled, as seen at $b b$, the object of which is to fit more evenly the flattened margins $b' b'$ of the electrotype-shell. The depth of the frame is made to correspond with the height of type, so that the electrotype may at the one operation of backing up be made to correspond with other type-matter in the printer's form.

Letter C is a representation of the top plate

of the mold, having a handle, G, on the back of it for holding the mold when clamped together for the introduction of the type-metal. On the under side of the plate is a core, D, attached to it by screws $g' g'$ for the purpose of giving or causing a hollow in the foot of the casting when it is required, but may be removed and another substituted.

Letters i are pins in the top plate for holding it steady on the frame B.

Letters F are clamps for holding the mold together by means of the thumb-screws I and I.

Having now described the construction of our improved mold, we will state our mode of using the same.

We first prepare the article to be electrotyped in a common printer's chase and surround it by rules of the same height and of the thickness required by the beveled edges of the mold frame B. The object of this is to obtain a flat margin, so that the shell may be held firmly and evenly on the bed-plate of the mold, and therefore this preliminary preparation of the shell becomes essential to the successful application of the invention of which it forms a part. After having locked the article in the chase it is submitted to the battery, and when thick enough is taken out and the back of it is tinned. The shell is then laid face down upon the bed-plate A and the beveled edges $b b$ of the frame B are fitted upon the flattened margins $b' b'$ of the shell. The top plate, C, is then put on, and by means of the clamps the whole is tightly secured together. The mold-block is then placed on end, having the handle thrown backward and downward. The object of this backward inclination is to prevent the metal from coming in contact with the tinned surface of the shell while running down into the mold.

All parts of the mold should be heated so as to melt tin before being put together to make the cast.

It will be obvious that various applications may be made of the mold for making two or more casts at the same time, either of the same or of different sizes, by means of cross-partitions, so as to hold the shells firmly down.

Having now described our invention and mode of application, we will proceed to state

what we claim and desire to secure by Letters Patent of the United States:

The use of the mold-frame B, or its equivalent, substantially for the purpose hereinbefore set forth, in combination with the bed-plate A, top plate, C, and clamps, and handle G, or their equivalents, for the purposes sub-

stantially as hereinbefore described, for back-
ing electrotype-shells.

A. D. FARMER.
RANSOM RATHBONE.
